GRATE

Norman James and Joseph J. Zurenda, Jr.,
Edwardsville, Pa.

Application February 8, 1939, Serial No. 255,336

1 Claim. (Cl. 122—374)

This invention relates to grates, and has for one of its objects the production of a simple and efficient grate for furnace boilers and the like, wherein means are provided for circulating water through the grate, to increase the life of the grate and to reduce the danger of the grate becoming burned out, to a minimum.

A further object of this invention is the production of a simple and efficient furnace grate, the parts of which may be readily assembled and thoroughly braced to provide a sturdy and unitary structure.

Other objects and advantages of the present invention will appear throughout the following specification and claim.

In the drawing:

Figure 1 is a top plan view of the grate;

Figure 2 is a transverse sectional view taken on line 2—2 of Figure 1;

Figure 3 is a longitudinal sectional view taken on line 3—3 of Figure 1;

Figure 4 is a perspective view of one end of one of the grate bars;

Figures 5, 6, 7 and 8, are transverse sectional views illustrating different design types of grate bars.

By referring to the drawing, it will be seen that the grate comprises a pair of headers or box-like members 10 which are arranged in spaced relation. These headers or box-like end members carry the grate bars 11 which are arranged in between the headers or box-like members 10, as shown in Figure 1. The grate bars 11 are preferably triangular in shape in cross-section, 35 having their flat upper surfaces 12 extending in a horizontal plane and arranged in flush relation with respect to the top face of the headers or box-like members 10, as shown in Figure 3. Each grate bar 11 is provided preferably at the 40 ends thereof with an extending collar 13 triangular in formation and these collars of the grate bars 11 fit in suitable openings formed in the inner faces of the headers 10 and are preferably welded to provide a unitary structure. Because 45 of the shape of the connection joint twisting of the grate bars 11 with respect to the headers will be resisted. Each header 10 is provided with an outer sealing plate 14 and the outer side of each header is left open while assembling the device, 50 until the ends of the grate bars 11 are welded to the headers 10. The plates 14 are then welded in the position shown in Figure 3. One of the headers 10 is provided with a plurality of inlet pipes 15 and the other header 10 is provided 55 with an outlet pipe 16. The grate bars 11 are

inserted slightly above the lower face of the headers 10, as shown in Figure 3.

The inlet pipes 15 are preferably connected to the bottom of the boiler and the outlet pipe 16 is preferably connected to the top of the boiler 5 to provide a proper circulation through the grate and the boiler.

These grate bars 11 are preferably braced transversely by means of the transversely extending spacing strips 17 which are welded or otherwise secured to the bars to provide a substantial integral structure. These bars 11 preferably taper toward their lower ends to provide wide outlet openings which increase in width below the upper faces of the bars so as to prevent the 15 fuel from clogging between the bars. These bars 11 are preferably braced from below by means of a plurality of transversely extending supporting members 18 which extend under the bars, as shown in Figure 2, and rest upon suitable side 20 rods or members 19 which fit against the side walls of the furnace 20. These rods or members 19 are also braced and supported by means of the transversely extending strips 21 which pass through the side walls of the furnace in the manner as shown in Figure 2. The bars 18, 19 and 21 may be suitably spaced and increased or decreased in number as occasion may demand. The grate is preferably mounted in the conventional manner so that the rear end is slightly 30 elevated with respect to the front end of the grate facilitating circulation of the water as well as facilitating the removal of the ashes etc., by pulling in the conventional manner.

In Figures 5, 6, 7 and 8 I have illustrated four 35 modified types of grate bar designs, wherein the grate bar may be modified as to its particular design without departing from the spirit of the invention.

It should be understood that the present type 40 of grate will provide a maximum surface which is acted upon by the water passing through and circulating through the grate and that the mounting and assembling of the grate bars with respect to the headers 10 will provide a very economical 45 and efficient arrangement for the construction of a grate, whereby water may circulate freely through the headers as well as through the grate bars which communicate at their respective ends with the headers. The grate bars although being 50 hollow to provide for this circulation between the headers are at the same time thoroughly braced and supported in a manner to prevent the grate from sagging and breaking.

The grate is adapted to be supported within the 55

fire-box of the furnace in such a manner as to permit proper expansion and contraction.

It should be further understood that the circulation of water through the grate will greatly 5 increase the life thereof and will reduce the possibility of burning out to a minimum. The spaces between the grate bars will provide sufficient draft and the sweating of the grate and grate bars will facilitate combustion providing 10 sufficient moisture because of this sweating to reduce the danger of obnoxious fumes. Furthermore, the water which passes through the grate will become preheated before passing to the conventional boiler to which the outlet pipe 16 may 15 pass in the usual manner.

Having described the invention, what is claimed is:

A grate of the class described comprising a pair of hollow end members having flat upper faces,

water inlet means for one end member, water outlet means for the other end member, hollow grate bars triangular in cross-section communicating with the end members and extending between the end members and arranged in spaced relation with respect to each other, said grate bars having their upper faces extending in a horizontal plane and flush with the upper faces of the end members, each grate bar having a reduced collar at its end of triangular formation, the end members having apertures of triangular formation to receive the collars to resist twisting strain of the bars with respect to the end members, the collars being welded in the apertures to provide a unitary structure, and the bars and end members having 10 circulating communication with each other. 15
